(57) **CLAIM**

The ornamental design for a device cover, as shown and described.

DESCRIPTION

FIG. 1 is a first perspective view of a first embodiment of a device cover, taken from above.

FIG. 2 is a second perspective view of the first embodiment of the device cover, taken from below.

FIG. 3 is a top view of the first embodiment of the device cover of FIG. 1.

FIG. 4 is a bottom view of the first embodiment of the device cover of FIG. 1.

FIG. 5 is a back view of the first embodiment of the device cover of FIG. 1.

FIG. 6 is a front view of the first embodiment of the device cover of FIG. 1.

FIG. 7 is a left-side view of the first embodiment of the device cover of FIG. 1.

FIG. 8 is a right-side view of the first embodiment of the device cover of FIG. 1.

FIG. 9 is a first perspective view of a second embodiment of a device cover, taken from above. The crosshatched pattern shown on the views of the second embodiment is meant to represent fabric (e.g., a woven fabric), and is understood to be distributed uniformly over the surface of the claimed design upon which the pattern occurs.

FIG. 10 is a second perspective view of the second embodiment of the device cover, taken from below.

FIG. 11 is a top view of the second embodiment of the device cover of FIG. 9.

FIG. 12 is a bottom view of the second embodiment of the device cover of FIG. 9.

FIG. 13 is a back view of the second embodiment of the device cover of FIG. 9.

FIG. 14 is a front view of the second embodiment of the device cover of FIG. 9.

FIG. 15 is a left-side view of the second embodiment of the device cover of FIG. 9; and,

FIG. 16 is a right-side view of the second embodiment of the device cover of FIG. 9.

The broken lines represent features of the device cover which form no part of the claimed design.
